DRIVE CIRCUIT FOR COUNTING TUBES

John E. Adams, Newtonville, Mass., assignor to Sylvania Electric Products Inc., Salem, Mass., a corporation of Massachusetts

Application August 24, 1956, Serial No. 606,142

11 Claims. (Cl. 315—84.6)

This invention relates to electronic counting devices and more specifically to drive circuits for gas filled glow transfer counting tubes.

Electronic counting of electrical impulses is a relatively old concept. Perhaps the earliest practical system developed was the ring circuit. The circuit included a group of electron tubes arranged in a ring and operable one at a time. Each tube, as it conducted current, designated a digit or other unit of data. Recently, many types of counting tubes have become available which incorporate several counting stages within one tube envelope. These tubes are generally, although not necessarily, constructed to provide for a count of ten and may be cascaded to provide a decimal counting system to any order of magnitude desired. The count at any instant can be read out from the activated stage in each tube.

One category of these counting tubes is composed of the so-called gas filled glow transfer counting tubes of which there are many differing types. All of the types, however, are multiple element tubes wherein a glow on one of the elements indicates visually and electrically a unit of data. Each impulse reaching the tube is counted and indicated by the change of the position of the glow from one element to another element in a predetermined pattern.

This invention contemplates the use of a glow transfer tube employing a central anode and three sets of cathodic electrodes. One set of the cathodic electrodes serves as the main or count indicating cathodes, and the other two sets are the so-called guide electrodes or guides. The transfer action of these tubes requires a driving circuit to convert input pulses into signals which are capable of switching the position of the glow from a main cathode to intervening guide electrodes and then on to the next main cathode in proper sequence.

The envelope of the tube is gas filled and has a disc-shaped anode located at its center. Arranged in an annular row about the anode are thirty (for a decimal counting system) equally spaced rod-like cathodic electrodes. Every third cathodic electrode is designated as a main or count indicating cathode. These main cathodes may be electrically connected together but generally one or more are arranged to provide independent electrical outputs. The remaining cathodes are divided into two groups, all of the members of each group being connected together to form two sets of guide or transfer electrodes. Switching of the glow from one main cathode to the next main cathode to effect a count is accomplished in the following manner. The potential of one set of guide electrodes is lowered to the point where the glow will leave its position on the main cathode and transfer to the nearest guide electrode of that set. The potential of the second set of guide electrodes is then lowered while the potential of the first set is allowed to return to its normal value. When the potential on the second set is sufficiently lower than that on the first set, the glow will transfer from its position on a guide electrode of the first set to the adjacent guide electrode of the second

set. The potential of the second set of guide electrodes is then allowed to return to its normal value. The normal potentials on the second set of guide electrodes and on the main cathodes are such that the glow will then move from the second electrode to the adjacent main cathode. Thus, the glow is moved in a predetermined direction from one main cathode via two guide electrodes to the next main cathode to effect a count.

The result described above is achieved by means of a particular driving circuit for the tube. The driving circuit must provide appropriate signals of proper potential, wave shape, and time relationship for each input pulse received. A simple circuit in which an input pulse is applied directly to one set of guide electrodes and through an appropriate delay circuit to the second set of electrodes may work satisfactorily in some applications. It has been the practice, though, to provide some amplification for the input pulses to improve performance.

At the other end of the scale, some very complicated circuits have been designed to produce in response to the input pulses being counted, signals to the guide electrodes which are nearly ideal in wave shape and timing. In fact, it is unnecessary that wave shapes be idealized, but it is highly desirable that reliability of counting be maintained and that the drive circuit be capable of operation at frequency rates at least as high as those at which the counting tube itself can operate. Neither the circuit of the simple type with its inherent unreliability nor the complicated circuit with its elaborate and expensive components has adequately filled these needs.

It is therefore an object of my invention to provide an electron discharge impulse counting circuit capable of operating at high input frequencies.

It is another object of this invention to provide a highly reliable electron discharge impulse counting circuit.

It is a further object of this invention to provide a driving circuit for delivering a set of output pulses or switching signals in response to and in timed relationship to each input pulse.

40 In general, the present invention consists in a drive circuit and glow transfer counting tube operable in response to input pulses or signals as modified by the drive circuit. The drive circuit develops the switching signals for application to the guide or transfer electrodes by utilization of the leading edge, the crest, and the trailing edge of the input pulse. The leading edge is utilized to excite a first tube which transfers the ionization path in the counting tube from a main cathode to a guide electrode. The leading edge also excites a second tube and the crest temporarily maintains conduction in that second tube. The output of the second tube is inverted with respect to the input pulse, and the trailing edge of the input pulse, as so inverted, in combination with the input pulse, causes excitation of a third tube which transfers the ionization path to a second guide electrode in the counting tube. Cessation of conduction of current in the third tube completes a cycle of transfer of the ionization path in the counting tube by switching it to the next main cathode. For a better understanding of the present invention, together with other objects, features and advantages, reference should be made to the following detailed description of a preferred embodiment and the accompanying drawing the single figure of which is a schematic diagram of one embodiment of the circuit and tube of the present invention.

70 The gas filled glow transfer counting tube 10 shown in the drawing includes a disc-shaped anode 11 surrounded by slim rod-like cathodic elements arranged in an annular row. Each third cathodic electrode 12, 12a, 12b, 12c and 12d is designated as a main or count-indicating cathode. In the drawing, there is illustrated a counting tube having only five rather than the ten stages previously

noted as being preferred for easy adaptation to decimal counting. This has been done to avoid unduly complicating the drawing and to simplify the explanation of the invention. The ten stage device would, of course, operate in the same manner as that shown and described.

Adjacent each main cathode are two guide electrodes. For example, adjacent main cathode 12 in a clockwise direction is a guide electrode 13, adjacent main cathode 12a in a clockwise direction is a guide electrode 13a. Similarly, the guide electrodes 13b, 13c and 13d are adjacent in a clockwise direction main cathodes 12b, 12c and 12d respectively. Going in a counter-clockwise direction, guide electrodes 14, 14a, 14b, 14c and 14d lie adjacent main cathodes 12, 12a, 12b, 12c and 12d respectively. Guide electrodes 13, 13a, 13b, 13c and 13d are all electrically connected together through the line shown as the innermost wiring ring in the drawing. Guide electrodes 14, 14a, 14b, 14c and 14d are similarly connected together through the middle wiring ring. Main cathodes 12, 12b, 12c and 12d are also connected together through the outermost wiring ring, cathode 12a being independent of direct connection to the ring for purposes explained below.

The anode 11 is connected through a resistor 15 to a point of high positive potential at the top of a voltage divider 16. The main cathode 12a is selected as the output cathode and is connected through a resistor 17 to another and lower point of positive potential 18 on voltage divider 16. An output terminal 19 is connected to the main cathode 12a. Similar connections may be provided for other main cathodes in those instances where it is desired to obtain additional outputs. In the embodiment shown, however, the four remaining main cathodes are all connected directly to the point of positive potential 18. A normally open reset switch 37 is connected between the main cathode 12a and ground to enable the glow to be removed from any other cathode and to be established on main cathode 12a as is more fully explained below.

A duo-triode 22 composed of a first triode section 22a and a second triode section 22b is shown. Separate triode tubes could, of course, be used instead of the duo-triode 22, since there is no interaction between the sections. The first set of guide electrodes 13, 13a, 13b, etc. is connected to the anode 20 of triode 22a. The second set of guide electrodes 14, 14a, 14b, etc. is connected to the anode 21 of triode 22b. The cathodes 23 and 24 of the duo-triode are connected together and to a point 39 of still lower positive potential on the voltage divider 16 than point 18. The control grid 25 of triode 22a is connected to the positive input terminal 26. The control grid 27 of triode 22b is connected through a resistor 28 to the input terminal 26 and through a capacitor 29 to the anode 30 of the triode 31. The anode 30 is also connected through a resistor 32 to the point of positive potential 18 on voltage divider 16. The cathode 33 of triode 31 is connected to the point of low positive potential 39, on voltage divider 16 and the control grid 34 is connected to the input terminal 26. An input grid resistor 35 is connected between input terminal 26 and the grounded input terminal 36.

In a typical circuit of the type described and shown, the tubes employed were a Sylvania Type 6802 as the glow transfer tube 10; a Sylvania Type 6J6 as the duo triode 22 and a Sylvania Type 6C4 as the triode 31. The voltage divider 16 provided 500 volts at its maximum tap from which point it was connected through the plate resistor 15 to the anode 11. The resistor 15 had a value of 430,000 ohms. The resistor 17 connected to the output terminal 19 had a value of 24,000 ohms and the voltage at its point 18 of connection to divider 16 was 100 volts. The plate resistor 32 had a value of 100,000 ohms and the differentiating circuit elements condenser 29 and resistor 28 had values of 10 micro-microfarads and 360,000 ohms respectively. The three cathodes of the triode 31 and

due triode 22 were connected to the point 39 of the divider 16 where the voltage was 7 volts. The input resistor 35 had a value of 150,000 ohms.

Considering the typical circuit for the moment with the cited voltages applied, a glow will take place immediately at one of the main cathodes. The particular main cathode which assumes the glow will be determined by some asymmetrical condition existing in the tubes or circuit which causes a lower potential to appear at one main cathode. A main cathode will assume the glow rather than a guide electrode because all main cathodes are lower in voltage than the guide electrodes. In the typical circuit being considered presently the main cathodes are at 100 volts derived from point 18 of the divider 16. It will be seen that the guide electrodes are at a potential greater than 100 volts. Although duo-triode 22 is "cut-off" by reason of the cathodes being connected to +7 volts at point 39 of divider 16 with the grids at ground potential, a certain minimum plate current is actually flowing in the two sections of duo-triode 22. This minimum current is of a value (e. g., a few microamperes) determined by the requirement for electrons to neutralize the stray gaseous ions present in the annular zone between the anode and cathode array of the glow discharge tube at points other than the zone of the existing visible glow. At this value of plate current, the voltage drop across the sections of duo-triode 22 is considerable. The voltage at the anodes 20 and 21 which is in fact the voltage on the guide electrodes is therefore also quite high, considerably in excess of the 100 volts on the main cathodes.

To initiate counting at a desired main cathode, a manually operable reset system is provided. In the circuit of Fig. 1, temporarily closing the normally open switch 37 grounds main cathode 12a placing it well below the potential of the other tube elements, and therefore cathode 12a assumes the glow. On reopening the switch to return the circuit to a normally biased condition the glow will remain on main cathode 12a since none of the counting tube elements is at a potential low enough to cause switching or transfer of the glow.

The action taking place in the circuit elements by which the glow is transferred from one main cathode to the next is described below.

Assuming the glow is taking place at main cathode 12a, switch 37 having been momentarily closed to ground cathode 12a, a circuit is completed from the top of voltage divider 16 through resistor 15, to anode 11, to cathode 12a, and through resistor 17 to a relatively low point 18 on voltage divider 16. Both sections 22a and 22b of duo-triode 22 remain just below cut-off in the absence of a signal on their control grids because their cathodes 23 and 24 are electrically tied to the point 39 of positive potential on divider 16. The anode 30 of triode 31 is electrically connected to point 18 of positive potential on divider 16, and its cathode is also returned to point 39 of low positive potential. Hence, triode 31 also remains non-conducting in the absence of a signal.

With the application of a positive input pulse across input terminals 26 and 36, the switching action begins. A sinusoidal pulse will be considered although pulses of other shapes can be counted by means of this invention with minor modifications.

The applied input pulse appears directly at grid 34 of triode 31 and at grid 25 of triode section 22a. Triodes 31 and 22a immediately begin to conduct current more heavily. The increasing current through triode section 22a causes a decreasing voltage to appear at anode 28 of that section. Anode 20 is directly connected to the set of guide electrodes which includes electrode 13a and the dropping voltage accordingly appears at 13a. The actual curve of potential drop at electrode 13a is an amplified inverted replica of the input signal. As the potential on guide electrode 13a drops sufficiently below that

of cathode 12a, the glow discharge from anode 11 transfers from main cathode 12a to guide electrode 13a.

At the same time, the voltage on the set of guide electrodes which includes electrode 14b must be considered. The voltage at that set of electrodes goes through the following changes. Triode 31, as mentioned above, begins to conduct more heavily when the input pulse is applied to its grid 34. The increased current through triode 31 develops a voltage across resistor 32 such that the voltage at the anode 30 appears approximately as the inverse of the input pulse.

The inverted voltage so obtained is differentiated by the circuit composed of condenser 29 and resistor 28. Therefore, the leading edge and crest of the applied input pulse as inverted and differentiated appear at the grid 27 of triode section 22b as a negative voltage and do not cause triode section 22b to conduct current.

The trailing edge of the input pulse, however, causes the current being passed by triode 31 to decrease. Correspondingly, the voltage developed across resistor 32 decreases and anode 30 rises in voltage. The rising voltage at anode 30 is coupled to the grid 27 of triode section 22b causing that section to begin to conduct current. As the conduction increases, the voltage at anode 21 and, of course, at the transfer electrodes including 14b drops, transferring the glow discharge to that electrode. During the occurrence of the trailing edge of the input pulse the voltage on the electrodes including 13a is rising as conduction through triode section 22a decreases, permitting the transfer of the glow from guide electrode 13a to 14b to occur.

The switching action is completed prior to the termination of the input pulse. With no further signal on the grids of triode 31 or duo-triode sections 22a and 22b, the voltage on anodes 20 and 21, and therefore on both groups of guide electrodes return to their normal bias potentials causing the glow discharge to shift to main cathode 12b.

Another explanation of the switching sequence is had by considering the voltage appearing at grid 27 of triode section 22b to be the result of combined effects. As the glow discharge shifts to guide electrode 13a, during the occurrence of the leading edge of the input pulse, the anode voltage at anode 30 of triode 31 is decreasing from its prior value to a value determined by the voltage at point 18 on the divider 16 less the voltage developed across resistor 32. Condenser 29, having previously become charged to the full value of voltage at point 18 during the quiescent period between pulses, tends to discharge to reach an equilibrium point with the voltage now present at its terminals. This, of course, causes the voltage at grid 27, the junction of condenser 29 and resistor 28, to drop, maintaining triode section 22b cut off.

However, as the input pulse crests and the voltage at anode 30 begins to go in a positive direction the rate of discharge of condenser 29 declines. The input pulse is also present on grid 27 directly by way of resistor 28, and as the rate of discharge of condenser 29 approaches zero, the directly applied input pulse is temporarily the only voltage present at grid 27 and causes the triode section 22b to conduct, lowering the voltage at anode 21 and guide electrode 14b to begin transfer of the glow discharge to that guide electrode. The trailing edge of the pulse is added to by the positive going voltage at anode 30 which causes a charging current to flow into the condenser making the junction of resistor 28, condenser 29 and grid 27 more positive than would be the case if the input pulse alone were effective on grid 27. This causes triode 22b to continue conduction until after triode 22a no longer conducts enough to retain the discharge on guide electrode 13a, and thereby the transfer of the discharge to guide electrode 14b is completed. As the condenser 29 becomes more fully charged, its charging rate decreases and reaches zero when the voltage on the

condenser returns to the value it had prior to the occurrence of the input pulse. This return closely follows termination of the trailing edge of the input pulse. With the return of the circuit to the steady state condition, the glow discharge transfers to the next main cathode.

With each successive input pulse, the sequence of actions is repeated, the glow discharge going in a clockwise direction from one main cathode to the next via the intervening guide electrodes. At each revolution of the glow discharge away from main cathode 12a, an output signal results and may be taken from point 19. This occurs because of the presence of resistor 17 between main cathode 12a and the other main cathodes. When the current of the glow discharge is flowing from cathode 12a through resistor 17 a voltage is developed across that resistor and is, of course, present between output terminal 19 and ground. When the glow discharge transfers to guide electrode 13a, the current through resistor 17 ceases and the voltage at output terminal 19 drops to the value of the voltage at point 18 on the divider. This is the same voltage which is present at all other main cathodes.

Conversely, when the glow discharge transfers to cathode 12a, the voltage across resistor 17 is initiated. In effect, then, an output pulse is present at terminal 19. Its duration is the length of time that the glow discharge is present at cathode 12a. Its frequency is one-fifth that of the input signal inasmuch as it takes five input pulses to cause the glow discharge to travel completely around tube 10. It is obvious that a cascaded arrangement of decade counter tubes can be used to count any finite quantity of units capable of representation by pulses.

Although a specific embodiment of the present invention has been described and illustrated, numerous modifications within the purview of the present invention will suggest themselves to those skilled in the art. For example, resistor 28 might be returned to ground rather than to the input voltage. This, however, would render the circuit more critical as to input wave shape, pulse crest value and frequency. Also, transistors might well replace the vacuum tubes in the drive circuit without departure from the concepts of the present invention.

Still another modification which suggests itself is the use of two or more circuits of the type illustrated with a single glow transfer tube. Thus, by the inclusion of another exciting circuit for the driving tube 22, for operation in reverse order, subtraction as well as addition can be carried out. Because of the foregoing, as well as other, modifications which immediately suggest themselves to those skilled in the art, the present invention should be limited only by the spirit and scope of the appended claims.

What is claimed is:

1. A drive circuit for a glow transfer tube for counting input pulses, said tube having an anode, a plurality of cathodes, a first plurality of guide electrodes, and a second plurality of guide electrodes, said cathodes and said guide electrodes being so disposed that adjacent each cathode in a clockwise direction there lies one of said first plurality of guide electrodes and adjacent each cathode in a counter-clockwise direction there lies one of said second plurality of guide electrodes, comprising means for establishing a glow discharge between said anode and one of said plurality of cathodes, means for lowering the potential of said first set of guide electrodes below that of said cathodes immediately in response to each of said input pulses to transfer said glow discharge from said one of said plurality of cathodes to the one of said first set of guide electrodes adjacent thereto, means for inverting and differentiating each of said input pulses, means for combining each of said input pulses with an inverted and differentiated pulse to provide a delayed pulse, means for lowering the potential of said second set of guide electrodes below that of said first set of guide electrodes in response to said delayed pulse to transfer

said glow discharge from said one of said first plurality of guide electrodes to the one of said second plurality of guide electrodes adjacent thereto, said glow discharge being transferred to another of said plurality of cathodes adjacent said one of said second plurality of guide electrodes upon increase of potential on said second plurality of guide electrodes above that of said plurality of cathodes on cessation of said delayed pulse.

2. Impulse counting apparatus comprising a glow transfer tube having a plurality of cathodes, a first plurality of guide electrodes, and a second plurality of guide electrodes, means for establishing a glow discharge at one of said cathodes, means for transferring said glow discharge to one of said first plurality of guide electrodes immediately upon occurrence of one of said impulses, means for inverting and differentiating each of said impulses, means for combining each of said impulses with an inverted and differentiated impulse to provide a delayed pulse, and means for transferring said glow discharge to one of said second plurality of guide electrodes in response to said delayed pulse.

3. A drive circuit for a glow transfer tube comprising a first vacuum tube for providing a first negative voltage pulse in immediate response to a positive input pulse, a second vacuum tube for providing a second negative voltage pulse in immediate response to the positive input pulse, a differentiating circuit connected to said second vacuum tube for differentiating said second negative voltage pulse, a third vacuum tube, means for combining the positive input pulse with the differentiated second negative voltage pulse, means for applying the output of said last-mentioned means to said third vacuum tube to produce a third negative voltage pulse delayed in time relative to said first negative voltage pulse and means connecting said first and said third vacuum tubes to said glow transfer tube to couple said first and said third negative voltage pulses thereto.

4. A drive circuit for providing sequential negative voltage pulses to a glow transfer counting tube in response to positive input pulses comprising means for converting said positive input pulses to negative switching pulses immediately upon occurrence thereof, means for inverting and differentiating each said positive input pulse, means for combining each said positive input pulse with an inverted and differentiated pulse, and means for converting the output pulses of said combining means into second negative switching pulses, and means for applying said first and said second negative switching pulses to said glow transfer counting tube.

5. A drive circuit for providing sequential negative voltage pulses to a glow transfer counting tube in response to positive input pulses comprising means for providing a first negative voltage pulse to said counting tube in response to the occurrence of a positive input pulse, said first negative voltage pulse being substantially an inverted replica of said input pulse and originating in timed relationship with the leading edge of said input pulse, and means for providing a second negative voltage pulse to said counting tube in response to the trailing edge of said input pulse.

6. A drive circuit for a glow transfer tube for counting input pulses comprising a first means for generating a first switching pulse in response to the leading edge of each said input pulse, a second means for generating a second switching pulse in response to the trailing edge of each said input pulse, said second means comprising means for inverting each said input pulse and means for differentiating each inverted input pulse, and means for coupling said first and second switching pulses to said glow transfer tube.

7. A drive circuit for a glow transfer tube for counting positive input pulses comprising a first vacuum tube connected in series with a first set of glow transfer electrodes in said glow transfer tube, a second vacuum tube

connected in series with a second set of glow transfer electrodes in said glow transfer tube, means for applying said input pulses directly to said first tube to increase conduction therein, said first set of glow transfer electrodes being immediately lowered in potential by the increased conduction in said first vacuum tube, means for inverting and differentiating said input pulses, and means for applying said input pulses and said inverted and differentiated pulses to said second vacuum tube to increase conduction therein and thereby to lower the potential of said second set of glow transfer electrodes.

8. A drive circuit for a glow transfer tube for counting positive input pulses comprising a first vacuum tube having at least an anode, a cathode and a control grid, the anode of said first vacuum tube being connected to a first set of guide electrodes in said glow transfer tube, a second vacuum tube having an anode, a cathode and a control grid, the anode of said second vacuum tube being connected to a second set of guide electrodes in said glow transfer tube, the cathodes of said vacuum tubes being connected together and to a source of operating potential, means for applying said input pulses directly to the control grid of said first vacuum tube, means for inverting and differentiating said input pulses and means for applying said input pulses in combination with said inverted and differentiated pulses to the control grid of said second vacuum tube.

9. A drive circuit for a glow transfer tube for counting positive input pulses comprising a first vacuum tube having at least an anode, a cathode and a control grid, the anode of said first vacuum tube being connected to a first set of guide electrodes in said glow transfer tube, a second vacuum tube having an anode, a cathode and a control grid, the anode of said second vacuum tube being connected to a second set of guide electrodes in said glow transfer tube, the cathodes of said vacuum tubes being connected, a third vacuum tube having at least an anode, a cathode and a control grid, a source of operating potential being connected between the anode and the cathode of said third vacuum tube, means for applying said positive input pulses to the control grids of said first and said third vacuum tubes, inverted replicas of said input pulses appearing at the anodes of said first and third vacuum tubes, and at said first set of guide electrodes in said glow transfer tube, a differentiating circuit connected to the anode of said third vacuum tube, and means for coupling input pulses directly and the output pulses of said differentiating circuit to the control grid of said second vacuum tube, the anode of said second vacuum tube and said second set of guide electrodes being thus lowered in potential after the lowering in potential of said first set of guide electrodes.

10. Pulse counting apparatus comprising a glow transfer tube having a plurality of circularly arranged cathodes, an anode, a first set of guide electrodes each guide electrode of said first set being adjacent in a clockwise direction one of said cathodes, and a second set of guide electrodes, each guide electrode of said second set being adjacent in a counterclockwise direction one of said cathodes, a voltage divider, means connecting said glow tube anode to a first point of high voltage on said divider, three vacuum tubes each having at least an anode, a cathode and a control grid, said first set of guide electrodes being connected together and to the anode of the first of said vacuum tubes, said second set of guide electrodes also being connected together and to the anode of the second of said vacuum tubes, said plurality of glow tube cathodes, less one, being connected together and to a second point on said voltage divider of lower voltage than said first point, a resistor connecting said one glow tube cathode to the remainder of said glow tube cathodes, an output terminal at the junction of said resistor and said one cathode, and a normally open momentary contact switch connected between said junction and ground, the cathodes of said first, second and third vacuum tubes

being connected together and to a third point on said voltage divider of lower voltage than said second point, the anode of said third vacuum tube being connected to said second point on said voltage divider, means for coupling said pulses to be counted to the control grids of said three vacuum tubes, a negative voltage pulse appearing immediately on the anode of said first vacuum tube and on said first set of guide electrodes in response to each of said input pulses appearing at the control grid of said first vacuum tube, a negative voltage pulse also appearing at the anode of said third vacuum tube, a differentiating circuit connected between the anode of said third vacuum tube and the control grid of said second vacuum tube, the output of said differentiating circuit and said input pulse appearing simultaneously at the control grid of said second vacuum tube, whereby a negative voltage pulse appears on said second vacuum tube anode and on said second set of guide electrodes subsequent to the appearance of a negative voltage pulse on said first set of guide electrodes.

11. A drive circuit for a tube for counting input pulses comprising three vacuum tubes each having at least a cathode, a control grid and an anode, means for providing anode voltage to said three vacuum tubes, means for providing operating potentials to said cathodes of said

three vacuum tubes, means for applying said input pulses directly to said control grids of the first and second of said vacuum tubes to initiate substantially immediate increased conduction in the first and second of said vacuum tubes, means including a first resistance for applying said input pulse to the control grid of the third of said vacuum tubes, a capacitor connected between the anode of the second of said vacuum tubes and the control grid of the third of said vacuum tubes, said first resistance and said capacitor comprising a differentiating circuit, means for applying the output of said differentiating circuit together with said input pulses to the control grid of said third of said vacuum tubes to cause increased conduction of current therein after a period of delay and connections for providing output signals from the anodes of said first and said third vacuum tubes to the tube for counting input pulses.
